EDWARD F. RAYMOND, OF SANTA FE SPRINGS, CALIFORNIA.

CUTTER BLADE.

Application filed March 10, 1925. Serial No. 14,430.

This invention relates to a rotary drilling tool employing blades, and pertains especially to the blade structure. Cutting of the formation through which such types of tools are advanced is performed by the shearing action of the blades. The primary object of the present invention is to provide a blade for such tools which will offer a maximum of cutting edge of such conformation as to 10 efficiently bite into and cut the formation. Another object of this invention is to provide a blade which is interchangeable thereby permitting removal and replacement, making it unnecessary by reason there- 15 of to perform blacksmith work on the job. In addition to the broader objects of this invention, there are certain details of structure, whereby a strong, durable, and economical rotary drill bit is obtained.

20 These objects are obtained by means of the embodiment of my invention illustrated in the accompanying drawing, in which:

Fig. 1 is an axial section through the lower end of a drill; Fig. 2 is a section as 25 seen on the line 2—2 of Fig. 1; and Fig. 3 is a perspective view of a blade.

Referring more particularly to the drawing, the blade is shown as incorporated in a rotary core barrel having a body. The body 30 is of tubular form and is split or divided diametrically to provide halves 5 and 5'. Adjacent the lower end the body is enlarged in diameter, tapered and threaded as indicated by 6. At the bottom of the threaded 35 portion the body is further expanded as indicated by 7, ending in a cylindrical portion 8.

Mounted upon the body is a sleeve 9 which 40 is integral and has the bore of its lower portion conforming in shape to the exterior of the body. The bore has an internal thread for meshing with the thread 6 on the body so that when screwed into position it holds the sections of the body together and provides a water space 10. Communicating with the water space 10 and leading through the body are water courses 11. The bore of the body forming the core retaining part is 45 enlarged in diameter at the bottom to re-

ceive a trimming ring, and key recesses extending longitudinally thereof.

The trimming ring is split axially to form halves 12 and 12'. The lower edge of the ring is provided with cutting teeth 13 serving to trim the core. Each half of the ring has a key lug as indicated by 14 and 14'. The key lugs seat in corresponding key recesses in the body thereby retaining the ring in position when the halves of the body are locked together. The ring also 60 serves to hold the blades of the tool in position.

The body of the tool is provided with slots to receive the blades. These slots have walls converging radially outwardly and diverging 65 upwardly. Each blade is of quadrilateral form and tapers in an axial direction the convergence being toward the cutting edge. The wall cutting face provided with cutting edge 15 of the blade is fluted. The face provided with the lower cutting edge of the blade is likewise fluted, the cutting edge being rounded as indicated by 16. As seen from an inspection of Fig. 3, the nose or forward cutting edge of each blade is 75 fluted and the rear edge straight so as to be flush with the valleys of the flutes, thereby providing clearance for cuttings. It will be noted that a blade and its recess are so shaped that when the blade is inserted in 80 position, it cannot be moved radially outwardly by reason of it being thicker at the back than at the front. It cannot be moved downwardly for the reason that it is thicker at the top than at the bottom. The trimming ring retains the blade from moving 85 radially inwardly.

In the use of the tool, cores may be removed by removing the sleeve 9 to unlock the halves of the body and also the halves of 90 the trimming ring, thereby laying the bore of the tool open without disturbance of the core therein. Opening the tool in the same manner gives access to the blades so that they may be removed and replaced.

95 The shape of the cutting edge is such as to break up the formation and act more efficiently. The lineal length of cutting edge

for each blade is much greater than with the straight edge. The result is a tool which has a high degree of efficiency in cutting.

What I claim is:

- 5 An insertable blade for a rotary boring tool comprising a plate body of quadrilateral form having a wall trimming face intersecting a hole-advancing face, said faces being corrugated to form fluted cutting

edges sloping back to straight trailing edges, 10 the side faces of said plate body converging toward the corner formed by the intersection of said edges.

In witness that I claim the foregoing I have hereunto subscribed my name this 3rd ¹⁵ day of March, 1925.

EDWARD F. RAYMOND.
